UNITED STATES PATENT OFFICE

171,935

CHILD-SUPPORTING GROCERY CART

Charles Weldon Dodds, Long Beach, Calif.

Application April 17, 1953, Serial No. 24,562

Term of patent 3½ years

(Cl. D14—3)

To all whom it may concern:

Be it known that I, Charles Weldon Dodds, have invented a new, original, and ornamental Design for a Child-Supporting Grocery Cart, of which the following is a specification, reference being had to the accompanying drawing, forming a part hereof.

I claim:

The ornamental design for a child-supporting grocery cart, as shown.
